The ornamental design for a mobile phone, as shown and described.

DESCRIPTION

FIG. 1 is a perspective view of a mobile phone showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a first perspective view thereof, shown in a configuration of use;

FIG. 10 is a second perspective view thereof, shown in a configuration of use; and,

FIG. 11 is another perspective view of the design in FIG. 1, shown in a configuration of use.

The broken lines in FIGS. 1-8 depict portions of the mobile phone that form no part of the claimed design; the broken lines in FIGS. 9-11 depict environmental subject matter only and form no part of the claim.

1 Claim, 9 Drawing Sheets(56)
